UNITED STATES PATENT OFFICE.

HARRY A. SEDGWICK AND PATRICK J. SHEEHAN, OF MILWAUKEE, WISCONSIN.

ELECTROPLATING-MACHINE.

1,367,567.

Specification of Letters Patent.

Patented Feb. 8, 1921.

Application filed March 3, 1917. Serial No. 152,174.

To all whom it may concern:

Be it known that we, HARRY A. SEDGWICK and PATRICK J. SHEEHAN, citizens of the United States, residing at Milwaukee, in the 5 county of Milwaukee and State of Wisconsin, have invented new and useful Improvements in Electroplating-Machines, of which the following is a full, clear, concise, and exact description, reference being had to the 10 accompanying drawing, forming a part of this specification.

This invention relates to electroplating machines.

An object of the invention is to provide 15 a machine of the character stated, of increased efficiency.

A further object is to provide a machine of the character stated which shall be capable of practically continuous action, and 20 wherein the removal of the finished product, and the introduction of other material to be treated, may be accomplished during and without interruption of the plating operation.

25 A further object is to provide a machine of the character stated of materially increased capacity without substantial increase in the dimensions of such machine or in the driving power employed.

30 A further object is to expedite handling of both the finished product and the material to be treated and to facilitate the simultaneous treatment of different classes of material without intermingling thereof.

35 A still further object is to provide a machine of the character stated in which the electrolytic effect upon the purely mechanical parts thereof is minimized.

Other objects and advantages will herein- 40 after appear.

In the accompanying drawing, wherein is illustrated an embodiment of the invention.

Figure 1 is an end elevational view of the 45 machine, certain parts being shown in section;

Fig. 2 is a side elevational view, partly in section, of the machine;

Fig. 3 is an enlarged sectional view showing 50 in detail certain features of Fig. 2; and

Fig. 4 is a similar enlarged view showing further details of Fig. 1.

Referring to the drawing, the machine illustrated comprises, in general, a cradle 1 55 carrying series of alternately arranged anodes 2 and receptacles 3 for material to be

plated which will constitute cathodes, mounted for rotation within a tank 4 containing an electrolyte 5, said cradle being driven by a motor 6 acting through a gear 60 train 7, and provided with conductor rings 8, 9 and co-operating contact fingers 10 for supplying current to said electrodes, together with the usual fixed anodes 11 mounted in spaced relation on either side of 65 said cradle.

The cradle 1 comprises essentially a pair of similar and symmetrically arranged circular head members 12, held together by a series of elongated bolts 13 and maintained 70 in spaced relation by means of spacer sleeves 14 surrounding said bolts respectively and abutting the inner faces of said head members which are centrally bored for mounting upon a supporting shaft 15 upon which they 75 are keyed. The ends of said shaft are mounted in bearings 16 which are suspended from the upper edges of the tank 4 and secured thereto by suitable screws and bolts.

Each of the head members includes a circular rim 17 having exteriorly located gear teeth 18, a hub 19 and four radial webs 20 therebetween. Each web is bored to receive the ends of two bolts 13 as described, and the radially convergent edges of adjacent 85 webs are turned inwardly of the cradle to provide supporting surfaces 21 for the respective ends of the cathode receptacles 3. Each head member is further provided on its side exterior to said cradle with an annular flange 22 for carrying one of the conductor rings 8, 9.

The receptacles 3 are provided to carry the material being plated while supplying current thereto, and each of said receptacles 95 comprises an elongated box, substantially triangular in cross section and composed of wood, or other suitable material. Each box includes a pair of substantially triangular end members 23, a beveled bottom member 100 24 and side members 25, accurately fitted and secured to said bottom and end members. A removable cover 26 is also provided for each box and rests upon the outer edges of the end and side members which latter are 105 reinforced by blocks 27 to support the same. In practice, the boxes, preferably four in number, are supported within the cradle with their sides 25 extending substantially radially thereof and supported at their ends 110 by the radial surfaces 21 of the head members.

The boxes are of such length as to be readily insertible between the gear flanges 17 of the cradle heads when assembled, and are releasably held therewithin by means of specially constructed latches 28 which serve further to releasably secure the covers upon the boxes, each of which is provided with a latch at either end. Each latch comprises an elongated bolt 29 slidably mounted within 5 in suitable guides 30, 31 and having an upwardly bent and rounded knob 32 for engagement with the under side of the gear rim 17, the guide 30 being secured to the end of the box 3 by means of screws, while the 10 guide 31 is secured to the cover by means of bolts 33. An abutment plate 34 is also secured to the top of the cover 26 for engagement by the lower end of an adjustable locking member 35 which is screw threaded within 15 in a suitable bore 36 of the bolt 29. An integral hand wheel 37 is provided on the outer end of the locking member 35 to facilitate turning thereof, while the abutment plate 34 is provided with a pair of shallow 20 sockets 38, 39 to receive the end of the locking member for insuring proper positioning of the bolt 29 in different operative relations.

The latches when in the relation shown 30 in Fig. 3, serve to hold the covers upon the boxes and all in position within the cradle. To remove any box from the cradle, the locking members 35 located at its ends are screwed up out of engagement with their 35 sockets 38 thereby releasing the bolts 29 which may then be slid inwardly out of engagement with the rims 17, the knobs 32, however, being retained beneath the guides 30. The locking members 35 are now 40 screwed down to engage the sockets 39 whereby the cover is still held upon the box which may be lifted outside the cradle and tank and placed in suitable position for washing and emptying. The locking members 35 are again unscrewed to release the 45 bolts 29 which are then shifted so that the knobs 32 clear the guides 30 whereupon the cover 26 may be removed from the box. Each of the bolts 29 is provided with an eye 50 40 for the attachment of suitable hoisting tackle for raising and positioning the boxes.

The boxes have their bottoms, sides and covers perforated to permit circulation of the electrolyte therethrough, and the interior 55 of each box is provided with suitable conductive strips 42 extending along the bottom and sides thereof, while other conductive strips 43 may be secured to the inside of the box near the cover. All of the afore-mentioned conductors are in electrical connection with an interiorly located end strip 44 which extends outside the bottom of the box to form a contact 45 for engagement with a coöperating contact 46 carried by the hub 60 19 when the box is secured upon the cradle,

said contact 46 being electrically connected with the ring 8 through an insulated flexible conductor 47.

The contact 46 is mounted upon the outer end of a shouldered reciprocable insulating 70 plug 48 carried within a radial recess 49 in the hub 19, said plug being slotted at 50 to receive a pin 51 which extends through said slot and the adjacent portions of said hub for retaining said plug in suitable relation 75 within the hub while permitting a limited reciprocation of the former with respect to the latter. A helical spring 52 is compressed within an axial bore in the inner end of said plug for forcing the same toward the contact 45, said spring abutting an insulating disk 53 located within and completely filling the bottom of the recess. The engaging surfaces of the contact 46 and the plug 48 are formed substantially spherical to permit a 80 slight rocking movement of the former upon the latter. By the above described construction a positive engagement of the contacts is insured so long as the box is secured upon the cradle. 85

Each of the movable anodes 2 comprises a plurality of similar sections 54, mounted upon the bolts 13 outside the spacer sleeves 14 and insulated therefrom by means of non-conductive bushings 55 surrounding the latter. Each anode section includes a thin flat body portion enlarged at its ends and bored to fit snugly about the respective insulating bushings 55. The body portions are further provided with laterally extending fins or 90 webs 56 for increasing both the mass and the active surface of the section, said webs being tapered whereby, when assembled, their outer edges lie substantially upon radii of the cradle. Spacer blocks or washers 57 100 of wood, or other suitable non-conductive material, are mounted upon the bushings 55 adjacent the heads 12 to insure intimate contact between said anode sections when assembled and to insulate the adjacent sections 105 from said heads. Obviously the thickness of the blocks may be readily varied during assembly to compensate for variations in thickness of the sections. The sections of each anode are further electrically connected 110 by means of a conductive bar 58 lying across the outer ends thereof and secured to each by means of screws 59. Each bar 58 is electrically connected with the ring 9 by means of a flexible conductor 60 extending within 115 the periphery of the cradle and insulated therefrom whereby current is supplied to all the movable anodes.

The conductive rings 8, 9 are mounted upon the flanges 22 of the respective heads 12 and spaced therefrom by means of insulating blocks 61 located at intervals about the periphery of said flanges, and composed of wood or other suitable material, said rings being secured in place by means of con- 120

ductive bolts 62 passing through the flanges 22 and insulated therefrom. The ring 8, which is connected with the cathode members, is preferably composed of brass 5 although any highly conductive material may be employed. The ring 9, which is connected with the anodes is preferably composed of the same material as that which is being deposited by the machine. Being 10 connected with the anodes this ring is subject to corrosion by the current and is therefore built relatively heavy.

Current is supplied to the anode ring 9 from the positive side of a suitable direct 15 current source through the contact finger 10 which is resiliently mounted for continuous engagement with said ring, the cathode ring 8 being similarly connected with the negative side of said direct current source.

20 The afore-described cradle is driven by the electric motor 6 through transmission mechanism 7 including a flexible connection 63, a worm wheel 64 and worm gear 65, which latter is located upon a countershaft 25 66. Pinions 67 are keyed upon said countershaft in suitable relation to respectively engage the gear teeth 18 of the cradle heads whereby power from the motor is transmitted to the cradle at a greatly reduced speed.

30 A single pinion in mesh with one of the gears is usually sufficient for driving purposes.

In practice, the motor and gearing are mounted upon a base 68 which is releasably secured upon the upper edge of the tank 4 by means of suitable bolts. Said base, with its attached motor and transmission mechanism, upon release of said bolts, being bodily slidably in a horizontal direction away from 40 the cradle whereby the latter may be removed from the tank for inspection or repair.

The anodes 11 of the machine are in the form of rods or bars of suitable cross section 45 suspended within the electrolyte on either side of the cradle by means of suitable cross bars 69 resting upon the top of the tank, said anode bars being curved to extend substantially about the respective sides of the 50 cradle, being spaced a suitable distance therefrom to provide clearance and insure an efficient arrangement for electrical deposition. All of the aforesaid fixed anodes are electrically connected with the positive side 55 of the direct current source.

From the foregoing description it is apparent that the positive and negative movable electrodes are mounted upon the cradle in alternate relation with their adjacent 60 sides substantially parallel to provide a maximum of coöperating surface, and spaced from each other by an amount which is found in practice to be most advantageous. Since said electrodes are fixed with 65 relation to each other, the distance between

the respective anodes and cathodes does not change appreciably, such electrodes being maintained substantially in the desired relation.

The cathode boxes are removable singly 70 from the rotor for discharging and recharging and during this operation the plating action in the remaining boxes is uninterrupted. Furthermore, the material within each box is entirely separate from that in 75 the other box whereby classes of material differing in character may be handled at the same time without intermingling. The material undergoing treatment being further divided among the four quadrants of the 80 cradle the balance of the latter is substantially maintained, whereby the power necessary for driving the same is greatly reduced. Furthermore, during discharging and recharging of the cathode box the cradle 85 as a whole is not removed from the tank.

The electrical connections of the electrode being independent of the driving gears and shafting, there is present little or no tendency to plate the latter, the electrolytic action being practically confined to said electrodes.

What we claim as new and desire to secure by Letters Patent is:

1. In an electroplating machine, the combination with an electrolyte tank, of a cathode receptacle, an anode, and means supporting said receptacle and said anode within said tank in an exteriorly spaced relation and providing for joint movement 95 thereof within said tank.

2. In an electroplating machine, the combination with an electrolyte tank, of a plurality of alternately arranged cathode receptacles and anodes, and means supporting 105 said receptacles and anodes in spaced relation and providing for joint movement within said tank.

3. In an electroplating machine, the combination with an electrolyte tank, of a 110 cathode receptacle and an anode, and means supporting said receptacle and said anode in a spaced relation and providing for joint translatory movement thereof within said tank about an axis.

4. In an electroplating machine, the combination with an electrolyte tank, of a 115 rotatable cradle therein and a plurality of cathode receptacles and anodes carried by said cradle, said receptacles being individually eccentric to the axis of said cradle.

5. In an electroplating machine, the combination with an electrolyte tank, of a cradle rotatable therein, and a plurality of 125 alternately arranged cathode receptacles and anodes carried by said cradle, said receptacles and anodes being individually eccentric to the axis of said cradle.

6. In an electroplating machine, the combination with an electrolyte tank, of a 130

cradle rotatable therein, a plurality of anodes carried by said cradle and a plurality of sector shaped cathode receptacles mounted upon said cradle radially of its 5 axis and in alternate and spaced relation with said anodes.

7. In an electroplating machine, the combination with an electrolyte tank, of a cradle rotatable therein, a plurality of alternately arranged cathode receptacles and 10 anodes carried by said cradle, each of said anodes including a body portion and projecting webs tapered radially of the axis of said cradle.

15 8. In an electroplating machine, the combination with an electrolyte tank, of a cradle rotatable therein, a plurality of alternately arranged cathode receptacles and anodes carried by said cradle, said receptacles and anodes being in the form of sectors 20 assembled about the axis of said cradle and having their adjacent sides substantially parallel and suitably spaced.

9. In an electroplating machine, the combination with an electrolyte tank, of a cathode receptacle and an anode, means 25 supporting said cathode receptacle and said anode in a spaced relation and providing for joint translatory movement thereof within said tank, and a relatively stationary 30 anode extending within said tank.

10. In an electroplating machine, the combination with an electrolyte tank, of a cathode receptacle and an anode, means 35 supporting said receptacle and said anode in a spaced relation and providing for joint translatory movement thereof within said tank, said receptacle being in the form of a hollow box releasably secured to said sup- 40 porting means, and means for connecting said receptacle and said anode with a source of current.

11. In an electroplating machine, the combination with an electrolyte tank, of a cradle 45 rotatable therein, driving means for said cradle, a cathode receptacle and an anode carried by said cradle for joint translatory movement therewith, a relatively fixed anode extending within said tank, and means in- 50 dependent of driving connections for connecting said receptacle and said anode with a source of current.

12. In an electroplating machine, the combination with an electrolyte tank, of a cradle 55 rotatable therein, a cathode receptacle re- leasably secured upon said cradle, an anode for said tank, means for connecting said anode with a source of current and means for connecting said receptacle to a source 60 of current continuously while secured to said cradle, said latter connection being subject to interruption by removal of said receptacle from said cradle.

13. In an electroplating machine, the combination with an electrolyte tank, of a cradle 65

rotatable therein, an anode for said tank, a cathode receptacle releasably secured upon said cradle and comprising a hollow box having a removable cover, and a latch for said receptacle serving jointly to secure said 70 cover upon said box and to clamp said receptacle upon said cradle.

14. In an electroplating machine, the combination with an electrolyte tank, of a cradle 75 rotatable therein, an anode for said tank, a cathode receptacle releasably secured upon said cradle and comprising a hollow box having a removable cover, and a latch for said receptacle serving jointly to secure said 80 cover upon said box and to clamp said receptacle upon said cradle, said latch being operable selectively to release said receptacle from said cradle and thereafter to release the cover from said box.

15. In an electroplating machine, the combination with an electrolyte tank, of a cradle 85 rotatable therein, an anode for said tank, a cathode receptacle removably secured upon said cradle and comprising a hollow box having a removable cover, common means 90 for securing said cover upon said box and said box upon said cradle, said box and cover being composed of non-conductive material provided with perforations and conductive means carried interiorly of said 95 box.

16. In an electroplating machine, the combination with an electrolyte tank, of a cradle 100 rotatable therein, an electrode to be positively and releasably secured upon said cradle, driving means for said cradle, said cradle having means independent of said driving means for electrically connecting said electrode with a suitable source of current.

17. In an electroplating machine, in combination, an electrolyte tank, an electrode carrying cradle mounted for rotation therein, a motor and transmission means for driving said cradle mounted upon said tank and 110 movable as a unit with respect thereto, said cradle having means independent of the drive thereof for connecting the electrode thereon with a source of current.

18. In an electroplating machine, in combination, an electrolyte tank, an electrode carrying cradle mounted for rotation therein, driving means for said cradle, an annular conductor carried by said cradle to be electrically connected with the electrode 120 thereof so long as said electrode is carried by said cradle and a contact finger electrically connected with a source of current and adapted to coöperate with said annular conductor.

19. In an electroplating machine, in combination, an electrolyte tank, a circular cradle mounted for rotation with respect thereto, driving means for said cradle, a series of electrodes comprising anodes and 130

cathode members releasably secured to said cradle in alternate relation for movement therewith, said electrodes having their adjacent sides parallel and suitably spaced from each other, and means independent of the drive of said cradle and operable selectively for connecting all or certain of said electrodes with a suitable source of current.

20. In an electroplating machine, in combination, an electrolyte tank, a cradle

5 mounted for rotation therein, an anode and a cathode receptacle arranged in spaced relation upon said cradle for rotation therewith, and a relatively fixed anode extending within said electrolyte and about said cradle 15 for coöperation with said cathode receptacle.

In witness whereof we have each hereunto subscribed our names.

HARRY A. SEDGWICK.
PATRICK J. SHEEHAN.
